SHINKICHI TAMURA, OF KOBE, AND MASANORI WATANABE, OF TOKYO, JAPAN; SAID
WATANABE ASSIGNOR TO SAID TAMURA.

INTERNAL-COMBUSTION ENGINE.

1,402,111.

Specification of Letters Patent. Patented Jan. 3, 1922.

Application filed August 1, 1918. Serial No. 247,885.

To all whom it may concern:

Be it known that we, SHINKICHI TAMURA and MASANORI WATANABE, subjects of the Emperor of Japan, and the former residing at No. 11 Nakayamate-Dori Gochome, Kobe, Japan, and the latter at No. 39 Takecho, Shitaya, Tokyo, Japan, have invented certain new and useful Improvements in Internal-Combustion Engines, of which the following is a specification.

This invention relates to improvements in a cooling device for an internal combustion engine whereby air alone is drawn into the cylinders thereof when the supply of gaseous fuel and this air is designed to cool the cylinders and is exhausted without being subjected to any compression, in consequence serving to sufficiently cool the engine to allow the same to operate effectively without necessitating the provision of a usual water cooling means.

The object of the invention is to provide a device of this character which may be utilized during the period where the motor car is temporarily stopped, the actuation of the device serving to instantly stop the usual operation of the engine without separating the normally geared motor shaft and propelling shaft. During such stoppage of the engine air is drawn into the cylinder or cylinders by action of its suitable valves so that the cylinders may be cooled and scavenged at the same time the air is exhausted without being subjected to any compression.

The invention is clearly illustrated in the accompanying drawing in which:

Fig. 1 is a front elevation of an engine showing the improved cooling apparatus applied thereto.

Fig. 2 is a transverse sectional view thereof, partly in elevation.

Fig. 3 is an enlarged side elevation of the means for controlling the operation of the inlet and exhaust valves for the cylinders.

Figs. 4 and 5 are details of the valve means for controlling the gaseous fuel and air supply.

Referring now, in particular to the accompanying drawings there is provided an internal combustion engine including cylinders 1, in which operate pistons of a conventional type. The numeral 2 represents the power shaft of the engine; 3 its bearings; 4 the crank portions of the shaft 2; and 5,

the crank pins. The crank pins are of course connected to the connecting rods 6 and the pistons which operate in the cylinders as shown in Fig. 2.

The shaft 2 is provided with a toothed wheel 7, which is geared with a toothed wheel 8 rigidly connected to a cam shaft 9, so that the shaft 9 is rotated at one half of the speed of the shaft 2. The present gearing apparatus is not the essential part of the invention and any convenient device can be used therefor.

The controlling shaft 9 is provided with three cams 10, 11 and 12. These cams are arranged in one set for one cylinder. Hereinafter the description will be given to the set of cams and other devices according to this invention for one cylinder only, as those for another cylinder are the same as the former.

Cam 10 operates an inlet valve 15 for fuel or mixture of air and carbureted fuel through an inlet valve controlling apparatus 13, 14 and 15. Cam 11 operates an exhaust valve 19 through an exhaust valve controlling apparatus 17 and 18. These parts are the same as those for the usual type of engine. The characteristic features of this invention are cam 12 and a special apparatus associated therewith and the same will be more fully described as regards its construction and operation.

Cam 12 is engaged with a sliding rod 20, which in turn is connected to a member 22 through a link 21 and this link at its intermediate point is pivoted to the rod 17. This member 22 is connected to a wire 24 through its pin 23. Moreover, the member 22 is always pressed downward by means of a coil spring 25 which is juxtaposed between the said member and a stationary or fixed piece 95. This member 22 can, however, be raised against the action of the spring 25 when the wire 24 is pulled upward by a suitable mechanism as will be hereinafter described. 27 is a guide for the member 22.

The cam surfaces of the cams, 11 and 12 are diametrically opposed to each other. In the position shown in Fig. 1 and in full lines in Fig. 3, the cam 11 works on the exhaust stroke so that the exhaust valve controlling apparatus 17 and 18 is raised upward. This causes the link 21 to rock around its pivot point on the member 22 and so pulls up the rod 20 thereby preventing operation of said rod 20 by the cam 12. Therefore, in this

case, the motor will work as if there were no apparatus concerning cam 12 and its associated parts.

However, when the explosion in the cylinder of the motor is stopped and the rod 25 is pulled upwards to simultaneously stop the supply of fuel, parts 20, 21, 22, 23, 24 and 25 are brought to the positions shown in dotted line in Fig. 3, then the rod 20 is 10 pressed downward rocking the link 21 around its pivot point upon the rod 17, so that the cam 12 will operate to raise the rod and by reason of the arrangement of the member 22 in its raised position and the connection of the link as at 25 with the rod 17, the exhaust valve will be consequently opened and as the cams 11 and 12 are arranged to extend in opposite directions, when the cam 12 begins to move to its lowermost position the cam 11 will start on its movement to its uppermost position to prevent downward movement of the rod 17 so as to hold the exhaust valve open, as is apparent. This causes another opening of the exhaust valve, in addition to the usual opening of the said valve on the exhaustion stroke, on the compression stroke of the motor. Therefore the cylinder will be subjected to the following scavenging action, that is, on 25 the suction stroke, when the inlet valve is open, pure scavenging air comes into the cylinder without mixing with any carbureted fuel.

On the next or compression stroke, the 30 exhaust valve is opened by the operation of the cam 12 as just described. Therefore this scavenging air is not subjected to any compression and is exhausted into atmosphere without heating the cylinder by its compression heat as hitherto occasioned. On the next expansion stroke, the inlet valve is automatically opened by the vacuum in the cylinder so that scavenging air comes into it, which, in the next exhaustion stroke 40 is exhausted through the exhaustion valve now opened by the ordinary controlling of the rod 17.

One example of the device for holding up the rod 25 when the supply of the mixture of air and fuel gas is shut off, is shown 50 in Figs. 1, 4 and 5. This device consists of the wire 24 which is guided by a pulley or roller 24' and is fixed at its end to an arm 28' of a double armed lever 28-28'. 55 To the other arm 28 of this double armed lever is connected one end of the handling rope 28''. The lever is supported rotatably by means of a shaft 29, which is provided with a valve 29'. This valve controls the 60 supply of air through the air inlet tube or duct 30. When the rope 28'' is pulled, the valve 29' will shut off the passage of air through the duct 30 and at the same time the rod 25 is held up as stated. Thus as 65 air cannot enter through the closed duct

30, gaseous fuel is drawn through the duct 31 which is connected in a suitable manner with a carburetor (not shown) during the suction strokes of the engine pistons. However, when the valve 29' is opened, the suction in the duct 31 is relieved by atmospheric air entering the duct 30 and air is freely drawn into the engine cylinders. 70

As above described, the invention is provided with a special arrangement of cam 75 12 and its associated parts 20, 21, 22, 23, 24, and 25, by means of which scavenging air can be exhausted without compression, which otherwise is necessarily compressed on the compression stroke of the motor. 80 Therefore the supply of the scavenging air is doubled while preventing the heating of the cylinder by compression head and accordingly the cooling and scavenging action in the cylinder is considerably increased. 85 Consequently the cooling action of the engine according to this invention is very great, especially when the engine is used for a motor car, in which the working of the engine is rather conveniently stopped for 90 several minutes, so that the engine may be sufficiently cooled by air alone, instead of using the water cooling apparatus hitherto employed. The employment of this cooling device simplifies the construction of cylinder of the engine, decreases the initial cost 95 thereof and also the daily cost for operating.

What is claimed, is,

1. In an internal combustion engine, a 100 main shaft, cylinders having an intake and an exhaust, a secondary shaft normally geared with the main shaft, valves for the intake and exhaust of the cylinders, means between the secondary shaft and the intake 105 valves for operating said valves, cams on the secondary shaft, rods between certain of the cams and the exhaust valves, a supporting member adjustably mounted on the engine, a link pivoted to the supporting member at one end and having its medial portion pivoted to the adjacent exhaust valve operating rod, a rod pivoted to the opposite end of the link for coacting with the adjacent cam, and means for moving and 110 maintaining the member in the desired position.

2. In an internal combustion engine, a 115 main shaft, cylinders having an intake and an exhaust, a secondary shaft normally 120 geared with the main shaft, valves for the intake and exhaust of the cylinders, means between the secondary shaft and the intake valves for operating said valves, means for supplying fuel to the intake valves, cams 125 on the secondary shaft, rods between certain of the cams and the exhaust valves, a supporting member adjustably mounted on the engine, a link pivoted to the supporting member at one end and having its 130

medial portion pivoted to the adjacent exhaust valve operating rod, a rod pivoted to the opposite end of the link for coacting with the adjacent cam, and common manu-
5 ally operable means for adjusting the position of the supporting member and for simultaneously shutting off the supply of gaseous fuel to the intake valves.

3. In an internal combustion engine in combination with the secondary shaft of the engine, a cam on the shaft and a vertically movable exhaust valve operating rod, of another cam on the secondary shaft arranged directly opposite the first mentioned
10 cam, a vertically movable supporting member, a link pivoted to said member at one
15

end and having its medial portion ful-
crumed to the exhaust valve operating rod, another rod pivoted to the outer end of the link and connected with the second men-
20 tioned cam and manually operable means for regulating the position of the support-
ing member, substantially as described.

In testimony whereof we have hereunto set our hands in presence of two subscrib-
25 ing witnesses.
